UNITED STATES PATENT OFFICE.

FRITZ SCHWARZER, OF ST. GALLEN, SWITZERLAND.

LIFTING-JACK.

1,304,515.

Specification of Letters Patent. Patented May 20, 1919.

Application filed December 31, 1918. Serial No. 269,111.

To all whom it may concern:

Be it known that I, FRITZ SCHWARZER, a citizen of the Swiss Confederation, and residing at St. Gallen, Switzerland, have invented certain new and useful Improvements 5 in Lifting-Jacks, of which the following is a specification.

The present invention has reference to certain new and useful improvements in 10 jacks for lifting automobiles and the like, and it relates more particularly to a construction in which the weight sustaining member is stepwise lifted by the pumping action of a detachably hinged hand lever 15 and is retained in its relative position by an automatically acting spring member, which latter for the purpose of letting down the weight sustaining member is actuated preferably by the detached hand lever and can be 20 permanently retained in non-operative position by special mechanism, as will now be described in detail in connection with the accompanying drawing, in which Figure 1 represents a side elevation of the device, 25 partly in section, and Fig. 2 is a plan view thereof, the same reference numerals denoting like parts in the two figures.

The standard 1, rising vertically from the base 2, is strengthened by ribs 3 and 30 presents a housing of oblong cross-section in which a correspondingly shaped weight sustaining member 4 can freely reciprocate. The latter member has a preferably rounded 35 lower end 5 and supports at its upper end a member adapted to coöperate with the object to be lifted. As shown, this member is in the shape of a pointed pin 6, but it may, obviously, also be in any other form, for instance in that of a cradle to fit the wheel hub 40 or other part to be lifted. The weight sustaining member is provided at the two opposite narrow faces with rows of downwardly inclined rack teeth 7 and 8 respectively. In the front narrow wall 9 of the 45 standard is provided a slot 10 and above the latter the wall is thickened to form a channeled bearing bracket 11. For liftingly operating the rack member 4 there is provided a hand lever 12, the inner end of which 50 extends through the wall slot 10 and is designed to coact with its pointed extremity 12 with the row of feed teeth 7, as clearly shown in Fig. 1. The outer lever end is rectangularly bent-off, as at 13, to serve a 55 special purpose to be described farther on. The lifting lever 12 is normally suspended

from the bearing bracket 11 by means of a shackle or elongated loop member 14, so that it can readily be attached to or detached from the standard and can be pumpingly operated in the manner of a double-armed lever with the horizontal portions of the loop member serving as pivots. On the opposite standard wall near the upper end are provided laterally extending cheeks 15, and its upper rim is cut away to some extent, as at 16. A strong flat spring 17 is secured to the standard at its lower end by a bolt 18, which passes freely through a bore in the spring and carries between the latter and its flange head 19 a relatively stiff compression spring 20. In its upper portion the flat spring 17 is guided between the cheeks 15 and its upper extremity 17' is rectangularly inwardly bent and extends through the rim notch 16 into the domain of the rack teeth 8, so that normally the weight sustaining member is supported and relatively locked by this angle spring 17.

The raising as well as the locking mechanisms, obviously, operate in the manner of pawl and ratchet devices.

In operation the jack is placed beneath the automobile or other object to be lifted and its rack member 4 is forced up toothwise by pumpingly manipulating the hand lever, each such pumping oscillation raising the rack member the distance of one feed tooth 7 and the angle spring 17 alternately recedingly and supportingly coöoperating with the ratchet teeth 8, so that the weight sustaining member will always be under the operative action of the angle spring, on the forward and on the return stroke of the lifting lever and even if the latter is removed entirely.

The lowering of the load can be obtained in two different ways. In case the load on the rack member is relatively light, the lifting lever is unhooked from the bracket 11, its angle end 13 is inserted between the standard and the lock spring somewhat below the cheeks 15, and the lever is then laid over in upward or downward direction, when the lock spring will be forced to recede from out of the rack teeth 8, with the result that the rack member is now free to drop down into the standard.

If the supported load is great then the lock spring may be forced out of operative contact with the rack teeth 8 by any suitable tool, not specially shown, or even by hand,

- while the lifting lever remains in operative contact with the feed teeth. By pressing down on the free end of the hand lever the rack member is to be lifted just a little so that the lock spring head is eased and can readily be withdrawn from underneath the respective tooth 8. The rack member is then let down step by step, the respective vertically oscillatory movements of the lifting lever alternating with horizontally reciprocatory movements of the lock spring, so that every time the lifting lever is disengaged from the rack tooth just lowered for engaging beneath the next upper tooth, the support or lock spring is allowed to move forward to support and lock the rack member until the point of the lifting lever has again caught hold of the rack and supports its weight.
- 20 For moving and retaining the lock spring out of coöperation with the rack member for any length of time, it is pushed back on its securing bolt 18 against the action of the helical spring 20 far enough to recede beyond the outer edge of the cheek 15 and is then swung over sidewise.
- What I claim is:—
- 30 In a lifting jack, in combination, an oblong hollow standard having an elongated slot in the one narrow wall, and a bracket bearing extending from said standard at its upper end above said wall slot; a weight sustaining member operatively fitting the hollow of said standard, rows of ratchet teeth on the opposite narrow faces of said weight sustaining member; means for stepwise raising said weight sustaining member relative to said standard comprising a dou-

ble-armed lever, whose inner end is pointed and designed to coöperate with the one of said ratchet teeth rows and whose outer free end is rectangularly bent-off; and means for swingingly suspending said lifting lever from said bracket bearing comprising an elongated loop member pivoted at one end on said bracket and at the other end in said double armed lifting lever near its inner pointed extremity; means for supporting and locking said weight sustaining member against inadvertent lowering comprising a flat spring secured at the lower end to said standard and with its upper rectangularly bent-off portion designed to coöperate with the other one of said ratchet teeth rows; the rectangularly bent extremity of said lifting lever adapted to be inserted between said standard and said spring for temporarily forcing the latter out of coöperation with said weight sustaining member; and means for permanently keeping said lock spring out of operative contact with said weight sustaining member comprising guide checks extending from said standard, a bolt threading into the standard and passing freely through said lock spring, a flange head to 65 said bolt, and a helical compression spring surrounding said bolt and interposed between said lock spring and said bolt head for normally retaining the lock spring pressed against the standard, but with capability of 70 allowing the lock spring under outwardly directed pressure to recede far enough on its retaining bolt to be swung sidewise clear of the guide cheeks.

FRITZ SCHWARZER.
